US0D1048231S

(12) United States Design Patent (10) Patent No.: US D1,048,231 S
(45) Date of Patent:  Oct. 22, 2024

(54) WINGED FOAM HAND CHARACTER

(71) Applicant: She Persisted, LLC, Eden, MD (US)

(72) Inventor: Judith M. Hearthway, Eden, MD (US)

() Term: 15 Years

(21) Appl. No.: 29/940,526

(22) Filed: May 2, 2024

(51) LOC (14) Cl. 21-01

(52) U.S. Cl.

USPC D21/588; D2/615; D20/29

(58) Field of Classification Search

USPC D2/823; D6/601; D11/137, 157, 162;
D20/29; D21/588, 626, 658; D26/73

CPC A63H 3/14; A63H 3/36; A44C 1/00
